(57) **CLAIM**

The ornamental design for a data accessing device, as shown and described.

DESCRIPTION

FIG. 1 is a perspective view of a data accessing device showing the claimed design;

FIG. 2 is another perspective view of FIG. 1;

FIG. 3 is a front elevational view of FIG. 1;

FIG. 4 is a rear elevational view of FIG. 1;

FIG. 5 is a left side elevational view of FIG. 1;

FIG. 6 is a right side elevational view of FIG. 1;

FIG. 7 is a top plan view FIG. 1;

FIG. 8 is a bottom plan view FIG. 1;

FIG. 9 is a perspective view showing the data accessing device in a usage state;

FIG. 10 is another perspective view of FIG. 9;

FIG. 11 is a perspective view showing the data accessing device in another usage state; and,

FIG. 12 is another perspective view of FIG. 11.
